US00D997556S

(12) United States Design Patent (10) Patent No.: US D997,556 S
(45) Date of Patent: * Sep. 5, 2023

(54) BOX

(71) Applicant: Shenzhen Synchronization Technology Innovation Co., Ltd., Shenzhen (CN)

(72) Inventor: Weiran Zhang, Guangdong (CN)

() Term: 15 Years

(21) Appl. No.: 29/821,726

(22) Filed: Jan. 1, 2022

(51) LOC (14) Cl. 03-01

(52) U.S. Cl.

USPC D3/294

(58) Field of Classification Search

USPC D3/201, 212, 225, 269, 272, 273, 276,
